UNITED STATES PATENT OFFICE.

ANDREW J. BROWN, OF BALTIMORE, MARYLAND.

DESIGN FOR AN ADVERTISING-APRON.

SPECIFICATION forming part of Design No. 32,977, dated July 24, 1900.

Application filed June 2, 1900. Serial No. 18,900. Term of patent 3 years.

To all whom it may concern:

Be it known that I, ANDREW J. BROWN, a citizen of the United States, residing at Baltimore, Maryland, have invented and produced a new and original Design for an Advertising-Apron, of which the following is a specification, reference being had to the accompanying drawings, forming a part thereof.

Figure 1 is a plan view of the advertising-apron, showing my new design. Fig. 2 is a sectional view of Fig. 1, taken on the dotted line *x-x*.

Referring now to the drawings, A represents the body of the apron, which is rectangular in shape. Around the edge of the apron is a border *b*. Near to the top of the

body is a panel *B*, of rectangular shape, for advertising matter, having at its edge a border *c*, formed of a series of triangles placed apex to base between parallel lines. At each corner of the said border, instead of a triangle, is a square or two triangles placed base to base.

Having described my invention, what I claim as new, and desire to secure by Letters Patent, is—

The design for an advertising-apron as herein shown and described.

ANDREW J. BROWN.

Witnesses:

WM. T. HOWARD,
JOHN W. HEWES.
